LINT FREE CREEL

David L. Bohannon, Charlotte, N. C., assignor to Pneu-mafil Corporation, Charlotte, N. C., a corporation of Delaware

Application August 24, 1955, Serial No. 37,640

Term of patent 14 years

(Cl. D92—15)

FIG. 2.

FIG. 1.

Figure 1 is a perspective view of a lint free creel showing the new design; and

Figure 2 is a top plan view thereof.

The creel is mounted on a spinning frame of convenient length, as illustrated by the center break and dotted lines in the drawing.

I claim:

The ornamental design for a lint free creel, as shown and described.
